(57) **CLAIM**

The ornamental design for a folding bicycle, as shown and described.

DESCRIPTION

FIG. 1 is a right side view of the folding bicycle of the present invention;

FIG. 2 is a left side view thereof;

FIG. 3 is a rear view thereof;

FIG. 4 is a front view thereof;

FIG. 5 is a top view thereof;

FIG. 6 is a bottom view thereof;

FIG. 7 is a perspective view thereof;

FIG. 8 is another elevational view thereof;

FIG. 9 is a view of FIG. 1 shown in a folded position;

FIG. 10 is a view shown in another folded position;

FIG. 11 is a view shown in yet another folded position;

FIG. 12 is a view shown in a further folded position;

FIG. 13 is a view shown in yet a further folded position;

FIG. 14 is a view shown in still a further folded position; and,

FIG. 15 is a view shown in final folded position.

The claimed design is embodied in the collective appearance of the folding bicycle as seen in FIGS. 1 through 15. The folding bicycle is shown without the front and rear tires in FIGS. 9-15 for convenience of illustration.
